UNITED STATES PATENT OFFICE.

EZRA MILLER, OF JANEVILLE, WISCONSIN.

IMPROVEMENT IN CAR-COUPINGS.

Specification forming part of Letters Patent No. 38,057, dated March 31, 1863.

To all whom it may concern:

Be it known that I, EZRA MILLER, of Janesville, in the county of Rock and State of Wisconsin, have invented a new and useful Improvement in Car-Couplings; and I do hereby declare that the following is a full, clear, and exact description thereof, reference being had to the accompanying drawings, making a part of this specification, in which—

Figure 1 is an inverted plan view of my invention applied to the bottoms of two cars. Fig. 2 is a vertical longitudinal section through the spring-box, and a side elevation of Fig. 1. Fig. 3, Sheet 2, is an inverted plan view showing my invention applied to a tender and car. Fig. 4, Sheet 2, is a perspective sectional view of the spring-gate which controls the coupling-hooks.

Similar letters of reference indicate corresponding parts in the several figures.

This invention relates to certain new and useful improvements in coupling together railroad-cars, the objects of which improvements are chiefly to save life, not only of persons employed on and about the train, but also of passengers, who are always exposed to danger in passing and repassing from one car to another while the train is in motion, under the present-arranged system; also to save power in moving on curves.

As a practical railroad engineer, my experience has taught me that in order to prevent accident to persons coupling cars in the "yard" and elsewhere an automatic coupling or self-coupling must be employed, which will not require a person to get between the platforms of the cars to effect their coupling—an undertaking which is always attended with more or less danger under the best-regulated system. To obtain a car-coupling, therefore, which, while it is automatic in its operation, will answer all the purposes for which a coupling is intended, and which will be entirely practical in its application is the object of my invention.

To effect this object, the nature of my invention consists in a novel arrangement of two horizontal coupling-hooks, having double-beveled ends and vertical sides, one being arranged at each end of each car in such a relation to the other that the hook on one end of any car will couple with the hook on any other car, and while they prevent, to a

great degree, the unnecessary "shucking" or lateral and vertical motions of the cars, they form a positive and safe connection as long as the cars remain on the track; and in conjunction with these hooks it consists in the novel arrangement of a spring-gate with each coupling-hook, which yields and allows the hooks to couple, and then forms an abutment or stop which will prevent the hooks from casual displacement, as will be herein-after described.

It further consists in adapting the rear end of each coupling-hook to receive a rubber or other suitable spring-box, and at the same time to be connected by a pivot-joint, which latter allows the hooks all the required vibration, while the former prevents concussion in the coming together of the hooks in starting the train, as will be hereinafter described.

To enable others skilled in the art to make and use my invention, I will proceed to describe its construction and operation.

In the accompanying drawings, A A' represent portions of the beds or bottoms of two cars which are coupled together with my improved coupling.

C C' are two long-shanked hooks, the shanks of which may be made either round or square. These hooks have double-beveled sides a a' and acute or beveled hooking-surfaces b, which are perpendicular to the plane of the car-beds A A', as shown in Fig. 1, when the hooks are in position for coupling together. The upper and lower surfaces, c c, of these hooks are flat, and their rear shanked ends terminate in oblong quadrangular slots D D, terminated at their extreme ends by vertical pivots d d or eyes for the reception of vertical pivots. The hooked ends of these couplings project beyond the end of their respective car-platforms such a distance as that when the cars are coupled together a space of about an inch is left between the ends of the platforms, just sufficient to prevent them from rubbing one against the other. The ends of the hooks thus project under the ends of their respective opposite cars, and their hooking-surfaces b b are oblique to the line of draft, so that there will be a constant tendency of the hooks to keep together.

E is a stirrup, which is bolted to the bottom of the car-bed for the purpose of supporting and keeping the hook which passes through

it in its place, and also allowing it a slight lateral vibration. Each hook is furnished with one or more of these stirrups E, the side surfaces of which form abutments for regulating and confining the lateral vibration of the hooks within determined limits, and a block or blocks of rubber or other suitable spring may be arranged within these stirrups for receiving and counteracting the lateral thrust of the hooks.

F F are gates, which are made of metal of the obtuse or rectangular form shown in Figs. 1 and 4 of the drawings, and pivoted to the gudgeons e e, about which they play. These gates each consist of the two wings f f' and a central cavity for receiving a flat or round spiral spring, g, one end of which is affixed to the gudgeon e and the other end to the gate. The spring may be attached to a jointed device, R, or it may be coiled around the pintle e of the gate, so that its recoil will tend to rotate the gate, which rotation is controlled by the stop-pin h. The length of these gates is about equal to the thickness of the hooks, and they are arranged perpendicularly to the bed of the car in a plane with the vertical beveled surfaces a' a' of the hooks C C', which strike against them in coupling together, as will be hereinafter described. A gate, F, is provided for each hook, and it is arranged as near the edge of the platform of the car as possible and in such a relation to the hook on the opposite car and its own hook that when the two hooks approach each other the beveled surfaces a' a' of each hook will strike against the transverse wings f of their respective gates F F, which will yield and allow the hooks to couple together and then resume their former positions and keep the hooks together.

In order that a person, from the platform of the car, may effect the uncoupling of the hooks, chains i are connected to the wings j' of the gates F, which chains are also attached to vertical rods i', which project up through the platforms of their respective cars and carry on their upper ends hand-wheels i''. By turning either one of these rods i' in a direction which will wind up the chain i the gates F will be drawn back to the positions indicated in red lines, Fig. 1. Then by turning either of the hand-wheels on the end of the opposite car, which have chains j connecting with the backs of the hooks C C', either one or both of these hooks may be drawn back so far as to be disconnected from the other hook. Thus, on both ends of each car, I have two hand-wheels, one of the shafts of which connects with a hook while the other connects with a gate, and in this way the hooks may be set back and kept in this condition, so that they will not couple when the cars come together.

I have represented in the drawings the outline of a plan which I propose shall form the subject of a separate application for a patent, when it is thoroughly matured, for rendering the above described self-coupling an auto-

matic uncoupling in the event of the cars "jumping" the track. This plan is peculiarly applicable to my improved arrangement of coupling-hooks, and an understanding of it will illustrate the advantages of the hooks and their adaptation to the desired end. The rear end of each hook C being formed as described, the vertical pivot-pin d passes through a sliding block, d', which is applied within an oblong box, J, containing a suitable spring at k, which spring is confined within the box J by means of two plates, l l, affixed to the top and bottom sides of the box J. A sufficient longitudinal play is allowed the block d', and as the hook C is drawn outward in a direction with its length, this block compresses the spring k, and in this way the spring yields and receives all the concussion occasioned by the sudden striking together of the hooks in starting the train. The spring-box J, together with its appendages, are attached to and supported by the draw-bar K, which extends back along the center of the car, and is connected thereto by means of the king-bolt L, which connects the car with the trucks. The stirrup K' supports the draw-bar K, and its forward end passes through holes made longitudinally through the rear end of the spring-box and is connected with this box by a swivel-joint, which allows this spring-box, together with its coupling-hook C, to revolve around it. Now, it will be seen that by making the hook so that it can be readily turned either downward or upward I am enabled, by the attachment of a simple connection of levers and chains to the spring-box J, to keep the hook C always in a proper position for coupling to a similar hook, C', on another car, and also to turn this hook either upward or downward, so that it will not effect a coupling, or to so secure the hook that it will immediately disconnect itself from its fellow in the event of a car "jumping" the track. All of the hooks I propose to arrange in this manner, so that all may be operated as described.

The springs k, which are used in the spring-boxes, may be made of rubber or metal as may be desired, possessing sufficient strength and elasticity to receive the concussion at the starting of the train, and relieve the coupling-hooks from sudden jar.

The draw-bar K may be made of round or square rod iron, and its forward end should be so fitted into the spring-box J as to allow this box to turn freely around it.

A stirrup, n, may be used for supporting the forward end of the spring-box, which stirrup should be of sufficient size to allow the box J to turn in it.

The spring N, which is applied to the back of each hook C, is intended to keep these hooks in place for coupling together; but any kind of spring may be used for this purpose, applied in any suitable manner to the hooks.

I have shown in Fig. 1, Sheet 1, two kinds of spring-gates, one of which has a long curved

spring attached to its wing *f*, and applied to the outside of the gate. The other gate has no spring applied outside, but contains an helical spring, *g*, within it which is coiled around the fixed stud *s*, as above described, and as clearly shown in Fig. 4 of the drawings. I do not desire, however, to confine myself to the particular manner described for applying a spring to the pivoted gates.

The shucking of cars in motion is not always a necessary consequence of a bad road, nor is there any necessity to adopt a coupling to conform to these extreme motions of a car; but it generally arises from the fact that the coupling links, hooks, and other contrivances which have been applied to couple together the cars in a train, are made in such a manner as to allow a very wide space between the platforms of each car, and to form no positive connection of the cars, so that the slight motion of one car actually imparts an augmented motion to each succeeding car, and in this way the concussions upon the rolling-stock and rails are very great and destructive, and a very unpleasant movement is communicated to the cars. Besides, the traction of the wheels, caused by the shucking, upon the rails is greatly increased, particularly in "rounding curves," whereas if the cars are brought close together, leaving only sufficient space for them to conform to the grade of the road, these objections will be to a great degree obviated.

In Fig. 3, Sheet 2, I have shown a means of coupling a car to the "tender," and in this "tender-coupling" I use a spiral spring for keeping the hook up to its place. The hook itself is of the form above described; but instead of having a long vibrating shank, like the other hooks, it is connected to or forms a part of a laterally-sliding rod, which works in suitable guides applied to the frame of the tender. This sliding bar is allowed a sufficient play laterally to release the hook from a car-hook or to move it back and keep it in such a position that it will not couple. The draw-chain and gate and its draw-chain are also used with this tender-coupling as described for the car couplings; and this hook is also arranged so that it will couple with the hooks on either end of any car having my coupling applied to it.

With my improvements I dispense with the coupling or bumper boxes, which have been invariably been used in couplings which operate on the principle I adopt, and by dispensing with such boxes I am enabled to use hooks as large and strong as the boxes and hooks combined of other arrangements without increasing the first cost of couplings or carrying a greater weight than is carried when other coupling-hooks with boxes are used. Then, again, I can fit my couplings to all heights of platforms by simply "blocking under" a high car and attaching the coupling-hook to the

blocking. Again, I greatly reduce the length of a train of given capacity by using no coupling-boxes, the ends of the platforms of cars with my arrangement being faced with steel or other material, so as to prevent rapid wear. By reducing the length of a train I bring the weight nearer to the power, which is a great advantage in passing over vertical or around horizontal curves, as this prevents the loss of much power and wear and tear of the rails and wheels. I can also travel such curves with greater safety. The gist of my invention, therefore, lies in the practical adaptation of a simple hook disconnected from bumper-boxes to the purposes herein described, and in the adaptation of a gate for use in connection with couplings which couple and uncouple on the principle herein described.

In the application of my coupling-hooks to cars which have no platforms—such as freight-cars—the gates, and also the hooks, may be operated by a simple lever, the long arm of which will extend from the bottom of the car some distance above the roof of the car, so that a person can operate the coupling from the roof of the car, instead of from the platform.

Having thus described my invention, what I claim as new, and desire to secure by Letters Patent, is—

1. The combination of the double beveled coupling-hooks, the stirrups *E E*, and the springs *N N*, all constructed and arranged so as to operate in the manner and for the purposes described.
2. The spring-gate *F*, constructed, arranged, and operating substantially as and for the purposes described.
3. The combination of the laterally-located spring-gates *F F* with wings *f f'*, stop-pin *h*, and coupling-hooks *C C'*, substantially as and for the purposes described.
4. The double beveled hooks *C C'*, disconnected from any coupling or bumper box, constructed, arranged, and operating in the manner described.
5. The combination of the hooks *C C'*, vertical spring-gates *F F*, the draw-chains *i j*, and windlass-rods *i' i'*, substantially as described.
6. Forming in the rear ends of the coupling-hooks a longitudinal slot, *D*, adapted to receive a spring, or its equivalent, and to allow of the pivoting of the hooks at their rear ends, substantially as and for the purposes herein described.
7. The combination of the pivoted, slotted, shanked coupling-hooks with the forward support, *E*, and spring-gates *F F*, arranged substantially as herein described.

EZRA MILLER.
